PASTE CONTAINER

Carl R. Klok, Tippler, Wis.

Application October 11, 1938, Serial No. 234,437

9 Claims. (Cl. 221—78)

This invention relates to containers for paste, such as tooth paste or shaving paste, or similar material or substance, and more particularly to those that comprise a container body of fixed 5 shape and size, and a movable expeller for discharging the paste or similar material from a spout or nozzle provided for that purpose.

In a general way, therefore, this invention is in the nature of an improvement on the construction shown and described and claimed broadly in prior application Serial No. 189,372, filed February 8, 1938.

The object of the present invention and improvement is to provide a novel construction and arrangement whereby the expeller is movable transversely of the axis of the body of the container, so that the discharge from the space between the inner end of the expeller and one wall of the container body is laterally of said space, instead of in the same direction as the movement of the expeller, whereby a comparatively flat or flattened form of container may be used for this purpose, with the expeller on one of the broad sides thereof, and with the spout or discharge 25 nozzle located on the periphery or edge of the container body, instead of being axially aligned with the expeller, thus providing an article in simulation of a compact for cosmetics that can be conveniently carried in a pocket or hand bag or that may be laid on a table.

It is also an object to provide certain details and features of construction tending to increase the general efficiency and desirability of a paste container of this particular character.

To the foregoing and other useful ends, the invention consists in matters hereinafter set forth and claimed, and shown in the accompanying drawing, in which—

Fig. 1 is a perspective of a container embodying the principles of the invention.

Fig. 2 is a perspective of a package of paste that may be employed in filling the container.

Fig. 3 is an enlarged section on line 3—3 in Fig. 1 of the drawing.

Fig. 4 is similar to Fig. 3, showing a different form of the invention.

Fig. 5 is a view similar to Fig. 1, showing a different form of the invention.

Fig. 6 is an enlarged section on line 6—6 in Fig. 5 of the drawing.

Fig. 7 is a view similar to Fig. 1, showing a different form of the invention.

Fig. 8 is an enlarged section on line 8—8 in Fig. 7 of the drawing.

As thus illustrated, referring to Figs. 1, 2, and

3 of the drawing, the invention comprises a sheet metal container body 1 of fixed size and form, of substantially flat or flattened contour, with a discharge spout or nozzle 2 in the periphery or edge thereof, this nozzle having a removable cap 3, for keeping the container sealed. A sheet metal expeller 4 extends through one of the relatively broad sides of the container body, being formed to prevent disconnection of the expeller from the body, and to expel the paste in the container when pushed downwardly. To prevent leakage through or around the joint between the expeller and the container body, a sack or lining 5 of any suitable material, such as Cellophane, can be employed to hold the paste. The said sack or lining 10 can be perforated by any sharp instrument inserted through the spout or nozzle, and when the expeller 4 is moved downwardly, the paste will be 15 expelled or discharged.

As shown in Fig. 4, the construction is similar 20 to that shown in Fig. 3, but in Fig. 4 the flexible lining of Cellophane or other material is omitted, and in this case a tight and accurate fit between the expeller and the container body will be necessary, in order to prevent leakage.

In Figs. 5 and 6 the construction is similar to that shown in Fig. 3 of the drawing, but in this case a removable screw threaded side wall 6 is provided for reloading the container, so that the latter can be used for some time by reloading it 30 from time to time with a new package of paste.

In Figs. 7 and 8 the construction is similar to that shown in Fig. 4 of the drawing, but in this case the expeller 7 is rotary, instead of movable bodily, and is provided with screw threads 8 for 35 engaging the screw threads 9 on the interior cylindrical wall of the container body. When the expeller 7 is rotated, the paste in the container will be discharged or expelled from the nozzle, until the container is empty. Obviously, the 40 lining or sack of Cellophane or other flexible material previously mentioned can be used in the construction shown in Figs. 7 and 8, if such is necessary or desirable. But it can be omitted if the metal parts are cast and the screw threads 45 are accurately cut to provide a tight joint between them. Obviously, therefore, in each form of the invention, the expeller is on the broad side of the container, instead of being on the side of minimum dimension, and thus the entire device, 50 on a scale suitable for some things, can be held between the thumb and finger of the same hand while the paste is being expelled therefrom.

Thus, in each form of the invention, the movable expeller has movement into the container 55

body, or within the latter, in a direction at right angles to the axis of the container body, which axis extends through the spout or nozzle. Hence, in each form of the invention, the discharge is laterally from the space between the inner side of the expeller and the opposing wall of the container body, instead of being in the same direction as the downward or inward movement of the expeller. In each form of the invention the construction is such that a substantially flat or flattened container is provided, which can be readily carried in a handbag, or conveniently stored in a cabinet. But while paste or similar material is discharged from the container, the latter remains rigid and fixed in shape and size.

In each form of the invention, it is obvious that the outer wall of the expeller can be provided with an opening having a closure of any suitable or desired character, (see Figs. 1 and 2) so that the space inside the expeller can be utilized for any desired purpose, as for holding face powder or cosmetics of one kind or another, or any small articles that the user might wish to enclose therein.

It will be seen that the shape and form of the device constituting the article of manufacture is such that it is stable when in repose with said expeller upward on a shelf or other flat support. Again, in each form of the invention, it is also true that the device has a shape and form whereby it is equally stable when in repose with said expeller downward on the shelf or other flat support. In addition, in each form of the invention, the expeller projects a distance, practically its entire depth, from the container when the latter is full, thereby to practically utilize the entire capacity of the container, so that the latter can in effect be filled to capacity when sold.

Also, in each form of the invention, the depth of the expeller is preferably substantially the same as the depth of the container, as indicated in Fig. 4 of the drawing. Thus the outer end or side of the expeller never moves below the open upper side of the container, looking at the device in the position in which it is indicated in the drawing.

Again, in each form of the invention, means are provided at the open side of the container to prevent the expeller from coming out accidentally when in use. In Figs. 3, 4, and 6, said means consist of the formation shown at 10, while in Fig. 8 said means are the screw threads shown and described.

It will be understood, of course, that the invention is not limited to the use of any particular materials, for the body of the container, inasmuch as there are obviously many materials other than metal which can be used for this purpose, in order to insure enough stiffness or rigidity to maintain the desired fixed form and shape of the container.

Thus by the invention an article is provided of a flat or flattened character in simulation of a compact for cosmetics that can be carried in a pocket or in a hand bag or that may repose lengthwise on either side on a table, substantially like an ordinary compact. In this way, the invention not only provides a convenient receptacle for tooth paste, or other kinds of paste, but also provides an article that can be used as a compact for cosmetics or the like, or in which to carry things in addition to the paste. While the article shown and described is perfectly flat on its opposite sides, it is obvious that the requirements of the invention will be satisfied by a formation that

is more or less flat on each side so that it may be carried and handled in the manner of a cosmetics compact.

Furthermore, it will be seen that the discharge spout or nozzle 2 has its passage or outlet so formed that the paste is not only forced out laterally from the side of the container, but upwardly as well, whereby the outer end of the said spout or nozzle is substantially midway between the top and bottom of the substantially flat container, thus contributing materially to the said flat or substantially flat design the purpose of which is to simulate, as explained, a compact for cosmetics or other things. In this way, the article constituting the invention can be placed on a table, on either of its two flat sides, as the said location of the spout or nozzle will not interfere therewith.

It will be observed that when the sack or bag 5 is used, it serves to both insert and contain the 20 paste in the container, and to prevent leakage, thus preventing any smearing of the fingers. Thus, practically the entire capacity of the container is utilized when filled, as the said sack or bag fits or conforms to all interior wall surfaces 25 of the container.

Thus the expeller is movable but leakless, as provisions are made to prevent leakage of the paste between its sides and the sides of the container when the wide open side of the container is 30 down or on the under side of the article.

What I claim as my invention is:

1. A device of the class described, comprising a container body of fixed shape and size, with one side thereof open, having a discharge spout or nozzle, for discharging paste from the container, and a movable but leakless expeller in said open side, preventing leakage when the open side is down, having unyielding engagement with said container and operating laterally or transversely 40 of the axis of the base of said nozzle, to expel the paste, the body of paste practically fitting or conforming to the interior of the container, so that practically the entire capacity of the container is utilized when filled, all forming a substantially 45 flat or flattened article with two opposite sides, both when full and when empty of paste, in simulation of a compact for cosmetics that can safely be carried practically flatwise in a pocket or hand bag or that may repose lengthwise on either side 50 on a table, said expeller projecting from the container a distance when the latter is full, to practically utilize the full capacity of the container, with said device shaped and formed whereby it is stable when in repose on either side and means 55 on the inside of said body at said open side to prevent the expeller from coming out accidentally when in use.

2. A structure as specified in claim 1, said expeller having a closed utility chamber therein. 60

3. A structure as specified in claim 1, the depth of said expeller being practically or substantially the same as the depth of the container.

4. A structure as specified in claim 1, said expeller having an outer side which is practically 65 flush with the open side of the container when the latter is empty.

5. A structure as specified in claim 1, said expeller being on the side of the container having the maximum dimension, and the device being 70 adapted to be held between the thumb and finger of the same hand, while the contents are being expelled, the outer side of the expeller being engageable with the thumb or finger until the contents is entirely expelled. 75

6. A container for paste, comprising a body for holding the paste, the body of paste practically fitting or conforming to the interior of the container, so that practically the entire capacity of the container is utilized when filled, a discharge nozzle in position to discharge the paste laterally from the interior of said container, and an expeller fitting the interior of the container and adapted to effect the discharge of the paste, the bottom of the container and the top of the expeller providing substantially flat opposite sides, the distance between said opposite sides being less than the length and breadth of the container, whereby the latter may repose on either side on a table.
7. A container for paste, comprising a container body for holding the paste, a discharge nozzle for discharging the paste laterally from the interior of said body, and an expeller mov-
- able in the body to effect the discharge of the paste, said expeller comprising a hollow member containing a utility compartment for holding cosmetics or other articles.
8. A structure as specified in claim 6, said discharge nozzle having its outer end disposed substantially midway between the top and bottom of the container body, with a passage therein extending upwardly and outwardly from the bottom of the container body, whereby the latter can readily rest flatwise on either its top or bottom side.
9. A structure as specified in claim 6, comprising a bag or sack for inserting and containing the paste in the container, fitting or conforming to the interior formation of the container, thereby to practically utilize the entire capacity thereof when the container is filled.
